FILLING MACHINE

Ralph B. Bagby, Chicago, Ill.

Application July 2, 1937, Serial No. 151,563

3 Claims. (Cl. 226—75)

My invention relates to filling machines and particularly to novel automatic features applied to filling machines of the type illustrated in my prior Patent No. 2,032,163, dated February 25, 5 1936.

An object of my invention is to provide means in connection with such machines for progressively feeding containers to the filling nozzle and to a capping device, and to accomplish the desired result with very simple mechanism.

An object in the design of the mechanism utilized for the described purpose is to provide a step-by-step feeding motion and to so arrange the parts that the conveyor chain is stationary 15 two thirds of the time. This is accomplished by utilizing a pawl and ratchet, the movement of the pawl being effected by a crank. Furthermore, the mechanism is designed to provide for raising of the container so that the filling nozzle 20 enters therein, then lowering the container at substantially the rate of filling of the container, and then at the point where the predetermined quantity has been delivered, suddenly dropping the container thereby breaking off the stream 25 with no stringing out or dripping. The desired result is best accomplished by the use of a cam having the proper shape.

A further advantage in construction consists in the provision of a resilient arm against which 30 the cam acts with the result that while the movement is positive, yet there is sufficient resilience to avoid breakage in case of lack of register of the containers with the filling and capping apparatus.

Another point of advantage in the construction is in that the containers or jars are fed and delivered at the same end of a machine, thus adapting the device for one-man operation.

Other advantages will appear hereinafter in 40 connection with the detailed description.

My invention will be more readily understood by reference to the accompanying drawings, in which:

Fig. 1 is a side elevation of a filling machine arranged in accordance with my invention;

Fig. 2 is a plan view of that portion of the machine relating to the automatic operation of filling and capping;

Figs. 3 and 4 are sectional views on the lines 50 3—3; 4—4 of Fig. 2;

Fig. 5 is a sectional view on the line 5—5 of Fig. 1; and,

Fig. 6 is a sectional view on the line 6—6 of Fig. 2.

55 In the machine of my invention I provide a

frame, indicated generally by the numeral 10, the frame having a top 11 and a laterally disposed feed table 12. On the frame top is disposed a hopper 13, cylinder and piston 14 and a motor 15. The motor drives a sprocket 16 through a suitable gear box, and a sprocket chain 17 through a second sprocket wheel drives a cam shaft 18 journalled in the frame.

At one end, the shaft 18 has a crank provided with a crank pin 9 that engages a slot 20 in a 10 rocker 21 mounted on a bracket 22. The crank pin 9 travels in a circle at uniform speed. The pivot bearing at the lower end of bracket 22 is positioned so that crank pin 9, through rocker 21, moves link 23 to the left during 240° of the 15 circular travel of 9, and moves 23 to the right during 120° of the circular travel of 9. In filling such emulsions as sour cream, ice cream, mayonnaise, etc., they will break down if pumped at too high speed. That is one limitation on filling 20 speeds. There is also a limit to the speed at which a glass or paper container can be moved intermittently, without toppling over. Since containers have to be lifted, filled and fully lowered while the conveyor is at rest, we have found 25 that the best division of the cycle for maximum production is to have the conveyor at rest $\frac{2}{3}$ of the cycle, and have it do its moving in $\frac{1}{3}$ of the cycle. A link 23 connected to the free end of the rocker extends horizontally and is 30 connected to an arm 24 having a pawl 25 pivoted thereto. The pawl engages successive teeth 26 on an annular ratchet, as best shown in Fig. 5, the ratchet being fixed to a vertical shaft 27 that carries one of the two sprockets 28 for the conveyor chain 29. This chain operates directly beneath the feed table 12 and has extended rivets or pins 30 that extend upwardly through a continuous slot 31 in the table. These pins serve as the propelling means or flights for the containers, certain of which are indicated in dotted lines in Figs. 2 and 4. The device adapts itself for feeding containers or bottles of different diameters by varying the length of the pawl 25; that is, for smaller or larger containers, the pawl 45 25 is replaced with a larger or shorter pawl. Guide flanges 32, 33 are provided on the table top for insuring travel of the containers in the desired path from the filling to the discharging points. It will be noted by reference to Fig. 2 50 that the supply and discharge of the containers is at the same end of the table and that a workman may attend to both duties.

At the point where the material is supplied to the containers, hereinafter referred to as the filling 55

station, the table top has a circular cut-out within which the upper end 34 of a lifter 35 is fitted. The lifter is bifurcated to permit the chain 29 to pass therethrough and the circular head is slotted to permit the conveyor pins to pass. The lifter at the filling station is actuated through a leaf spring 36 pivotally connected at one end to the lifter and at the other end to a bracket 37. The spring arm has a roller 38 intermediate its ends, the roller riding on a cam 39 fixed to the cam shaft 18.

This cam is of peculiar shape as shown in Fig. 3, and designed so that after the container has been raised to receive within it the filling nozzle, it will be lowered at a rate in proportion to the filling of the container. Preferably, it will be so arranged that the nozzle will remain approximately one-half inch below the level of the material being discharged into the container. At the point 49 on the cam, the drop will be sudden, thus breaking the stream and avoiding stringing or dripping of the material. In the event there should be lack of register between the container and the filling nozzle, the resilient arm 36 will deflect and thus avoid any breakage. Since the lifter and its filled container will drop rather suddenly, I provide a bumper 41 on the lower end of the lifter.

At the point where the cap is applied to the container, hereafter referred to as the capping station, the parts are substantially identical, there being a lifter 42, spring arm 43 and cam 44. The cam is so shaped that a rather quick movement is effected just as the caps are seated, this being followed by a quick drop-away with an adjustable bumper not shown for cushioning the drop of the lifter.

The capper, best shown in Fig. 1, is of a conventional type and since the details are not a part of this invention, it will not be described other than to state that the capping head 45 is adjustably supported on a standard 46 fixed to the frame top.

In operation, bottles indicated at 47 are placed between adjacent pins 38 and between the guides 32-33 at the entrance point. The chain travelling clockwise will slide the bottles along to the filling and capping stations and deliver them at the discharge end where they may be removed by the same operator who places the empty bottles in the conveyor line.

A machine constructed as described will be found to operate continuously and effectively through long periods without attention. The conveying and capping apparatus are separate from

the filling apparatus, the latter being adapted to be cleaned, sterilized and adjusted from time to time without interference with the mechanism here disclosed. Obviously the apparatus is capable of considerable modification and I do not wish to be limited, except as indicated in the appended claims.

I claim:

1. In a device of the class described, the combination of a motor-driven filling apparatus, a shaft continuously driven by the filling motor, a conveyor for moving containers toward and away from the filling nozzle of said apparatus, means including a pawl and ratchet wheel and a crank and rocker for actuating the same for operating said conveyor from said shaft by a step-by-step movement, whereby said conveyor is idle substantially two-thirds of the time, means for lifting a container from said conveyor into filling relation with a filling nozzle on said apparatus and for lowering said container at substantially the rate material is supplied to the container during the filling operation, and a resilient arm through which the lifting movement is exerted.

2. In a device of the class described, the combination of a motor-driven filling apparatus, a shaft continuously driven by the filling motor, a conveyor for moving containers toward and away from the filling nozzle of said apparatus, means including a pawl and ratchet wheel and a crank and rocker for actuating the same for operating said conveyor from said shaft by a step-by-step movement, means for lifting a container from said conveyor into filling relation with a filling nozzle on said apparatus and for lowering said container at substantially the rate material is supplied to the container during the filling operation, and a resilient arm through which the lifting movement is exerted.

3. In a device of the class described, the combination of motor-driven filling apparatus and capping apparatus, a shaft continuously driven by the filling motor, a conveyor for moving containers toward and away from a single operator and passing the filling nozzle and the capping apparatus, means for operating said conveyor from said shaft by a step-by-step movement, a pair of lifters, one at the filling station and one at the capping station, said lifters straddling said conveyor and being operated from beneath the conveyor, cams on said shaft for raising said lifters, and resilient arms for transmitting the cam movements to the lifters.
